UNITED STATES PATENT OFFICE.

EDWIN LONG, OF IOWA CITY, IOWA, ASSIGNOR TO EDMUND SHEPARD AND WILLIAM B. CARPENTER, OF SAME PLACE, AND REUBEN ELLWOOD AND ABRAM ELLWOOD, OF SYCAMORE, ILLINOIS.

WIRE-STRETCHER.

SPECIFICATION forming part of Letters Patent No. 322,460, dated July 21, 1885.

Application filed March 3, 1884. (No model.)

To all whom it may concern:

Be it known that I, EDWIN LONG, of Iowa City, in the county of Johnson and State of Iowa, have invented certain new and useful Improvements in Wire-Stretchers; and I do hereby declare the following to be a full, clear, and exact description of the invention, such as will enable others skilled in the art to which it appertains to make and use the same.

My invention relates to an improvement in devices for stretching wire, the object being to provide an effective wire-stretching device which can be conveniently taken to the top of a pole, building, or other position more or less difficult of access, a further object being to provide a wire-stretching device which is simple in construction, durable, and inexpensive.

With these ends in view my invention consists in certain features of construction and combinations of parts, as will be fully described, and pointed out in the claims.

In the accompanying drawings, Figure 1 is a view in perspective, and Fig. 2 is a plan view.

23 A represents a rack-bar, preferably flat, having ratchet-teeth or notches *a* on its opposite edges. The teeth or notches *a* are situated in such position with respect to each other that if any two successive teeth on the same edge be taken there will be a tooth on the opposite edge transversely opposite a point midway between the two aforesaid successive teeth. This arrangement of teeth I find the most simple and least expensive; but the bar might, if desired, be provided with a series of teeth at short intervals on each edge—as saw-teeth, for example—and when so arranged the relative positions of the teeth on the opposite edges would be of little importance.

40 One end of the bar A is conveniently provided with a perforation, B, through which a chain, *b*, or any other approved device is fastened for the purpose of securing the bar for operation.

45 The bar A is provided near its opposite end with outwardly-extending guides C, one on each side of the said bar, through which guides the branches of the U-shaped connecting-rod D pass. The extremities of the rod D are

turned at right angles, to form pivotal bearings for an operating-lever, E.

The lever E is constructed to embrace the bar A, and is provided with two pawls, F and G, pivoted between the branches *e* of the lever E, on opposite sides of the bar A. The shape 55 of the pawls is such that when the handle of the lever is reciprocated the pawls F and G will alternately be caused to engage the teeth *a*. For example, suppose the pawl F to be engaged with one of the teeth *a*, and the handle at right angles to the bar A. As the lever-handle is moved toward the perforated end of the bar A, the connecting-rod D will be drawn along the bar, and the heel of the pawl G will be gradually pressed against the edge of the 60 bar A, thereby causing the point of the said pawl to engage a tooth in advance of the one holding the pawl F. In this manner the rod D will be drawn along the bar A at each stroke of the lever, the pawls automatically engaging 65 the teeth on the bar A, as described. After the pawls have crept to the end of the bar A the lever may readily be slid to the opposite end of the bar by disengaging the pawls and holding the lever at right angles to the bar. 70

75 For the purpose of readily grasping a wire at any point a plate, H, is secured to the connecting-rod D. I find it convenient to provide the plate H with a perforation, *h*, sufficiently large to loosely receive the wire of 80 which the connecting-rod may be made, and slip the plate H on one of the branches of the rod D before attaching the said branch to the lever. The plate H is provided with two rotary cams, *g*, *g'*, pivoted on the same side of 85 the plate and so situated as to take a frictional grip on the wire when the same is placed between them. It will readily be seen that the greater the strain on the wire the tighter will the grip become.

90 One of the cams, *g'*, is provided with a handle, *h'*, for the purpose of releasing the wire, when desired, by turning the cam back.

The advantages of the device herein described are self-evident, combining as it does 95 strength, lightness, ready adjustment, effectiveness, and simplicity.

I am aware that it is not broadly new to em-

ploy a lever connected with a wire-clamping device in combination with a rack-bar, and also that lifting-jacks have been provided with a lever having two pivoted pawls operating against serrated faces of the standard, and hence I make no broad claim thereto; but, Having fully described my invention, what I claim as new, and desire to secure by Letters Patent, is—

10 1. In a wire-stretcher, the combination, with a rack-bar having teeth on its opposite edges and provided with guides, of connecting-rods provided on their outer or free ends with devices for grasping and releasing the wire, a lever pivoted upon the opposite ends of the connecting-rods, and pawls pivoted to the lever and adapted to engage the teeth on opposite sides of the rack-bar, substantially as set forth.

2. In a wire-stretcher, the combination, with a rack-bar having teeth on its opposite edges and provided with guides, of connecting-rods passing through the guides, an operating-lever pivoted to the connecting-rods and provided with pawls for engaging the teeth of the rack-bar, and a plate secured to the outer ends of the connecting-rods and provided with a cam-grip for holding the wire, substantially as set forth.

In testimony whereof I have signed this specification in the presence of two subscribing witnesses.

EDWIN LONG.
